UNITED STATES PATENT OFFICE.

WALTER B. UFFERT, OF HEMPSTEAD, NEW YORK.

ELECTRIC WINDOW-CLOSING DEVICE.

1,172,409.

Specification of Letters Patent. Patented Feb. 22, 1916.

Application filed April 23, 1915. Serial No. 23,461.

To all whom it may concern:

Be it known that I, WALTER B. UFFERT, a citizen of the United States, residing at Hempstead, in the county of Nassau and 5 State of New York, have invented certain new and useful Improvements in Electric Window-Closing Devices; and I do hereby declare the following to be a full, clear, and exact description of the invention, such as 10 will enable others skilled in the art to which it appertains to make and use the same.

The invention relates to an electric window closing device.

The object of the present invention is to 15 provide a simple, practical, and comparatively inexpensive window closing device adapted to be operated at one point by a switch and capable of simultaneously closing the upper and lower sashes of all of the 20 windows of a building thereby enabling a building to be instantly protected by the closing of its windows in event of a storm and obviating the necessity of hurriedly closing them by hand.

25 With these and other objects in view the invention consists in the construction and novel combination and arrangement of parts hereinafter fully described, illustrated in the accompanying drawings and pointed out 30 in the claims hereto appended, it being understood that various changes in the form, proportion and minor details of construction may be resorted to without departing from the spirit or sacrificing any of the advantages of the invention.

In the drawings Figure 1 is a front elevation partly in section of a window provided with an electric window closing device constructed in accordance with this invention, 40 Fig. 2 is a side elevation of the same, the top plates being omitted to show the construction more clearly, Fig. 3 is a plan view of the window closing device, Fig. 4 is an enlarged detail view of one of the pulleys 45 illustrating the arrangement of the ratchet and sprocket teeth, Fig. 5 is a vertical sectional view of the window frame illustrating the arrangement of springs, Fig. 6 is a detail perspective view of the top plate for 50 the pulley casing, Fig. 7 is a detail view of a portion of the double pawl.

Like numerals of reference designate corresponding parts in all of the figures of the drawings.

55 In the accompanying drawings in which is illustrated the preferred embodiment of the

invention, 1 and 2 designate upper and lower sashes slidably mounted in a window frame or casing 3 and connected by chains 4 and 5 with counterbalancing weights 6 and 7. The 60 sprocket chains 4 and 5 pass over upper pulleys 8 and 9 having sprocket teeth 10 and 11 also provided with reversely arranged ratchet teeth 12 and 13. The weight 6 of the upper sash is sufficiently heavy to raise the 65 said upper sash to its closed position when the said sash is free to move and the weight 7 is slightly less than the weight of the lower sash which will close automatically when it is free to move.

The pulleys or rotary elements 8 and 9 are mounted in casings 14 which are open at the top to enable the chains to be readily placed on and removed from the pulleys or rotary elements. The casings are composed 75 of spaced sides and a connecting bottom portion and they are provided at the bottom and at the upper ends of their sides with ears or attaching portions 15 and 16 for the reception of screw or other suitable fastening devices for securing them to the window frame or casing. Each pulley casing is equipped with a top plate 17 which is transversely curved to arch the pulley or rotary element. Each of the top plates 17 is provided with an attaching flange 18 which is secured to the window frame or casing above the pulley.

The window sashes are held at any desired adjustment by means of a double pawl composed of spaced sides or members 20 and 21 and a transverse connecting portion 22. The sides or members 20 and 21 are pivotally mounted intermediate of their ends in brackets 23 and they are provided at their lower 95 ends with upwardly and downwardly projecting teeth 24 and 25. The upwardly projecting tooth 24 engages the ratchet teeth 12 which are shouldered to prevent the outer portion or side of the pulley or rotary member 100 from moving downwardly and permitting the weight 6 to raise the upper sash to its closed position. The downwardly projecting tooth 25 of the side or member 21 engages the ratchet teeth 13 of the other pulley or rotary member 9 which has its teeth shouldered to prevent the outer side or portion of the rotary member or pulley from moving upwardly and permitting the lower sash to close.

110 The chains and the sprocket teeth prevent heavy sashes from slipping over the pulleys.

but when the device is employed with light sashes the ordinary sash cord and weight may be used in connection with a smooth pulley. The transverse connecting portion 5 22 which may be either formed integral with the sides or members 20 and 21 or constructed separate therefrom is provided with a central upwardly extending bifurcated stem or arm 26 which is connected by a rod 10 27 with a transverse plate 28 which connects a pair of slidable cores 29. The slidable cores 29 extend into solenoid magnetic coils 30 which are suitably mounted upon a base plate 31 which is provided at one end with an upwardly extending flange or portion 32. The base plate 31 is also provided at the other end with upwardly projecting arms 33 which are connected by a transverse rod 34. The magnetic solenoid coils are arranged in 15 20 circuit with the coils of the window closing devices of the various other windows of a house or building and when the circuit is energized the cores are drawn inwardly into the coils thereby swinging the upper portion 25 of the double pawl inwardly and withdrawing the lower portions and the teeth carried thereby from engagement with the ratchet teeth of the pulleys or rotary elements. This permits the upper and lower sashes to 30 35 close automatically by gravity. The double ratchet pawl is normally maintained in engagement with the ratchet teeth of the pulleys or rotary elements by means of a coiled spring 35 secured at one end to the transverse rod 34 and connected at its other end to the transverse plate 28. When the coils are energized and the slidable cores are drawn inwardly, the spring 35 is placed under tension and is adapted to withdraw 40 45 the cores from the coils when the circuit is deenergized.

In order to enable the upper and lower sashes to slide freely without binding the window frame or casing is equipped at the 45 opposite side to that at which the pulleys are mounted with upper and lower springs 36 and 37 each secured at one end and having its other end free. The springs 36 and 37 which are bowed yieldably engage the 50 sashes and prevent the same from binding.

While the window closing device is shown applied at one side of the window only in the drawing, it may if desired be arranged at each side of a window especially where 55 extremely large sashes are to be raised and lowered.

What is claimed is:—

1. In a window closing device of the class described the combination with upper and 50 lower sashes, rotary elements provided with reversely arranged ratchet teeth, weights, flexible connections arranged on the rotary elements and connected with the weights and with the sashes, the latter being automatically closable by gravity when free to move,

a double pawl provided with reversely arranged teeth engaging the ratchet teeth of the rotary elements and means for operating the pawl to release the sashes.

2. In a window closing device of the class 70 described, the combination with upper and lower sliding sashes, rotary elements provided with ratchet teeth, separate flexible connections arranged on the rotary elements and connected with the said sashes and provided with independent weights, the weight of the upper sash being heavier than the latter and the lower sash being heavier than its weight whereby the sashes are automatically movable to their closed position by gravity, 80 means for engaging the ratchet teeth for holding the sashes in an open position and electrically controlled means for releasing the rotary elements to permit the sashes to close by gravity. 85

3. A window closing device of the class 90 described including upper and lower sashes, rotary elements provided with reversely arranged ratchet teeth, flexible connections arranged on the rotary elements and connected with the sashes and provided with weights, said sashes being automatically movable by gravity to their closed position, a pivotally mounted member provided with reversely arranged teeth engaging the 95 ratchet teeth for holding the sashes in an open position and an electromagnet connected with the said pivoted members for withdrawing the same from engagement with the ratchet teeth to permit the sashes to close. 100

4. In a window closing device of the class 105 described the combination with upper and lower sashes, rotary elements provided with ratchet teeth, flexible connections arranged on the rotary elements and connected with the sashes and provided with weights, said sashes being automatically movable by gravity to their closed position, a pawl provided with means for engaging the ratchet teeth for holding the sashes in an open position, 110 and a solenoid having a core connected with the pawl for withdrawing the same from engagement with the ratchet teeth.

5. In a window closing device of the class 115 described the combination of a window frame, and upper and lower sashes, rotary elements mounted on the window frame and provided with ratchet teeth, flexible connections arranged on the rotary members and connected with the sashes and provided with 120 weights, a double pawl composed of spaced sides pivotally mounted on the frame at one side thereof and provided with means for engaging the ratchet teeth, said pawl being also provided with a stem extending above 125 the top of the window frame, solenoid coils arranged upon the window frame or casing and provided with slidable cores, a plate connecting the cores, a rod extending from the plate to the said stem, and a spring connect- 130

ed with the plate for withdrawing the cores when the solenoids are deenergized.

6. In a window closing device of the class described the combination of a window frame, and upper and lower sashes, rotary elements mounted on the window frame and provided with ratchet teeth, flexible connections arranged on the rotary members and connected with the sashes and provided with 10 weights, a double pawl composed of spaced sides pivotally mounted on the frame at one side thereof and provided with means for engaging the ratchet teeth, said pawl being also provided with a stem extending above 16 the top of the window frame, a plate mount-

ed upon the top of the window frame and provided with upwardly extending arms, a transverse rod connecting the arms, solenoid coils mounted on the plate in rear of the said rod, cores operating in the coils, a transverse plate connecting the cores, a rod connecting the plate with the stem of the pawl and a spring connecting the transverse rod with the plate for withdrawing the cores. 20

In testimony whereof I affix my signature 25 in presence of two witnesses.

WALTER B. UFFERT.
